CLAIM

The ornamental design for a package of transaction cards, as shown and described.

DESCRIPTION

FIG. 1 is a front perspective view of a package of transaction cards of a first embodiment of the present invention; FIG. 2 is a front plan view of the invention illustrated in FIG. 1;

FIG. 3 is a rear plan view of the invention illustrated in FIG. 1;

FIG. 4 is a right side view of the invention illustrated in FIG. 1;

FIG. 5 is a left side view of the invention illustrated in FIG. 1;

FIG. 6 is a top view of the invention illustrated in FIG. 1;

FIG. 7 is a bottom view of the invention illustrated in FIG. 1;

FIG. 8 is a rear perspective view of the invention illustrated in FIG. 1;

FIG. 9 is a front perspective view of a package of transaction cards of a second embodiment of the present invention; FIG. 10 is a front plan view of the invention illustrated in FIG. 9;

FIG. 11 is a rear plan view of the invention illustrated in FIG. 9;

FIG. 12 is a right side view of the invention illustrated in FIG. 9;

FIG. 13 is a left side view of the invention illustrated in FIG. 9;

FIG. 14 is a top view of the invention illustrated in FIG. 9;

FIG. 15 is a bottom view of the invention illustrated in FIG. 9; and,

FIG. 16 is a rear perspective view of the invention illustrated in FIG. 9.

(Continued)

The broken lines in the drawings illustrate portions of the package of transaction cards that form no part of the claimed design.
